CLAIM

The ornamental design for a combined latch housing and pivotal operating arm, as shown and described.

DESCRIPTION

FIG. 1 is a perspective view of a combined housing and pivotal operating arm showing our new design, the broken-line showing of the rotary bolt components being for illustrative purposes only and forming no part of the claimed design;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof;

FIG. 7 is a left side elevational view thereof; and,

FIG. 8 is a top plan view thereof, with the operating arm shown pivoted to an open position.
